(57) **CLAIM**

The ornamental design for a shoe, as shown and described.

DESCRIPTION

FIG. 1 is a front perspective view of a shoe, showing the new design;

FIG. 2 is a lateral side view thereof;

FIG. 3 is a medial side view thereof;

FIG. 4 is a top view thereof; and,

FIG. 5 is a rear perspective view thereof.

The broken lines shown in the drawings illustrate portions of the shoe that form no part of the claimed design. The unshaded surfaces form no part of the claimed design.

A right-foot shoe is illustrated in FIGS. 1-5. A second embodiment of the design includes a left-foot shoe, which is a mirror image of the views of the first embodiment.
